FRANK CRAWFORD, OF LOS ANGELES, CALIFORNIA, ASSIGNOR OF ONE-HALF TO
CHARLES C. BURNETT, OF LOS ANGELES, CALIFORNIA.

FRICITION-TOP CAN-SEALER.

1,392,867.

Specification of Letters Patent.

Patented Oct. 4, 1921.

Application filed October 27, 1919. Serial No. 333,714.

To all whom it may concern:

Be it known that I, FRANK CRAWFORD, a citizen of the United States, residing at Los Angeles, in the county of Los Angeles and 5 State of California, have invented new and useful Improvements in Friction-Top Can- Sealers, of which the following is a specification.

My object is to make a friction top can 10 sealer and my invention consists of the novel features herein shown, described and claimed.

Figure 1 is a fragmentary side elevation of a friction top can sealer embodying the 15 principles of my invention, parts being broken away and shown in section and the view being taken looking in the direction indicated by the arrow 1 in Fig. 2, after the can is sealed.

20 Fig. 2 is a top plan view looking in the direction indicated by the arrow 2 in Fig. 1, parts being broken away and shown in section.

Fig. 3 is a horizontal sectional detail on 25 the line 3—3 of Fig. 1 and looking downwardly as indicated by the arrows.

Fig. 4 is a fragmentary vertical cross section on the line 4—4 of Fig. 1 and looking in the direction indicated by the arrows.

30 Fig. 5 is a fragmentary sectional detail on the same plane as Fig. 1 and showing the parts in position to seal the can.

The base 1 is flat in side elevation and substantially oval in plan and the base 1 is 35 adapted to be rigidly secured to a floor or bench by screws 2. The post 3 extends upwardly from near the rear end of the base 1. A platform 4 extends forwardly from the post 3 in vertical alinement with the forward part of the base 1 and a considerable 40 distance above the base. The platform 4 is adapted to receive a can 5 to be sealed. A bearing bracket 6 extends forwardly from the upper end of the post 3 and a vertical bearing 7 is formed in the forward end of 45 the bracket 6 in vertical alinement with the center of the platform 4. The drive shaft 8 is mounted in a shaft housing 9 and has a driving belt pulley 10 upon its rear end. A 50 bifurcated bearing 11 extends downwardly from the rear end of the housing 9 and the extreme upper end 12 of the post 3 fits in the bifurcation of the bearing 11 and the pin 13 is inserted through the bearing 11 and the 55 end 12 so as to pivotally mount the housing

9 and shaft 8. A pintle 14 extends downwardly from a sleeve fitting upon the shaft 8 against the forward end of the housing 9 and an expansive coil spring 15 fits around the pintle 14 against the housing 9 and fits 60 against the spring seat 16 at the upper end of the post 3 and the upper side of the bracket 6, the tension of the spring being exerted to press the forward end of the shaft 8 upwardly to a limited extent. 65

The spring seat 16 is formed integral with a supporting screw 16^a and the supporting screw is tapped into a boss 16^b formed at the upper end of the post 3 and at the upper side of the bracket 6, so that the spring seat 70 16^a may be adjusted up and down by rotating the screw.

A flange 17 is fixed upon the forward end of the shaft 8, a friction wheel 18 fits upon the shaft 8 against the flange 17 and a nut 75 19 is screwed upon the forward end of the shaft 8 against the friction wheel 18.

A hollow plunger 20 fits slidably in the bearing 7, a head 21 fits upon the lower end of the plunger below the bearing 7 and is 80 held removably in place by a set screw 22. An expansive coil spring 23 fits around the plunger 20 against the upper end of the bearing 7. A spring seat 24 is screwed upon the upper end of the plunger 20 against 85 the spring 23. The tension of the spring 23 is exerted to hold the plunger 20 elevated and the head 21 against the bearing 7.

An arm 25 extends outwardly and upwardly from near the upper end of the post 90 3, a branch arm 26 extends forwardly from near the upper end of the arm 25, a spring seat 27 is formed upon the branch arm 26, a spring 28 rests upon the spring seat 27, a lever 29 is connected to the bearing 30 95 formed at the upper end of the arm 25 by a pin 31 and the lever 29 extends forwardly and rests upon the spring 28. A pin 32 extends downwardly from the arm 29 through the spring 28 and through an opening in the spring seat 27 so as to hold the spring in place. A foot lever 33 is connected to a bearing 34 said bearing 34 extending upwardly from the base 1 at one side of the post 3 and the lever 33 extending forwardly 100 at one side of the platform 4 and below the platform. A link 35 is connected to the foot lever 33 in front of the bearing 34 and the link 35 extends upwardly loosely through the lever 29 and a nut 36 is screwed 110

upon the upper end of the link so that the tension of the spring 28 will raise the forward end of the lever 29 thereby raising the forward end of the foot lever 33 and so that 5 when the forward end of the foot lever 33 is forcibly depressed the forward end of the lever 29 will be pulled downwardly by the link 35. A fork 37 is formed upon the forward end of the lever 29 and the fork 37 10 straddles the upper end of the plunger 20 and rests upon the spring seat 24 so that when the lever 29 is pulled downwardly the spring 28 is compressed and the head 21 moved downwardly.

15 The cam shaft 38 is slidably mounted through the plunger 20 and has a conical cam 39 upon its lower end. The conical cam 39 operates in the vertical opening 40 formed through the head 21 in line with the opening in the plunger 20. A friction disk 41 is fixed upon the upper end of the cam shaft 38 above the fork 37 and in position to engage the friction wheel 18.

An arm 42 extends outwardly and upwardly from near the upper end of the post 3 at the opposite side from the arm 25. A branch arm 43 extends forwardly from near the upper end of the arm 42. A spring seat 44 is formed upon the branch arm 43. A 25 spring 45 rests upon the spring seat 44. A bearing 46 is formed at the upper end of the arm 42. A lever 47 has a bifurcated bearing 48 fitting the bearing 46 and a pin 49 extends through the bearings 48 and 46. A stud 30 50 is fixed in the lever 47 and extends downwardly through the spring 45 and through an opening in the spring seat 44 so as to hold the spring in place. A foot lever 51 is connected to a bearing 52 extending upwardly 35 from the base 1 at the opposite side of the post 3 from the bearing 34. A link 53 is connected to the lever 51 and extends upwardly loosely through the lever 47 and a nut 54 is placed upon the upper end of the link. The tension of the spring 45 is exerted 40 to hold the forward end of the lever 47 elevated to a limited extent. A fork 55 is formed at the forward end of the lever 47 and straddles the upper end of the cam shaft 38. A bearing face 56 is formed upon the 45 upper end of the hub of the friction disk 41 and rollers 57 and 58 are connected to the arms of the fork 55 and bear upon the face 56. A bearing plate 59 is fixed upon the extreme upper end of the cam shaft 38 on top of the rollers 57 and 58. A pin 60 is fixed 55 through an opening in the plunger 20 and extends into a slot 61 in the cam shaft 38 so that the cam shaft may reciprocate in the plunger 20 and so that the plunger 20 will be rotated by the rotation of the cam shaft, the cam shaft 38 being rotated by the contact of the friction disk 41 with the friction wheel 18, and so that the plunger 20 60 may be reciprocated in the bearing 7.

Arms 62, 63 and 64 extend radially from the lower end of the head 21 and webs 65, 66 and 67 extend from the head 21 between the arms 62, 63 and 64 the lower face 68 of the arms and webs being flat and at right angles to the bore 40. A bore 69 is formed through the head 21 across the bore 40 into each arm 62, 63 and 64 to form the spring seat and plunger seat 70 and a bearing bore 71 extends from the spring seat 70 to the end of the arm. The spring 72 fits in the spring seat 70, the plunger head 73 fits against the spring, a ball 74 is mounted in the inner face of the plunger head 73 to be engaged by the cam 39 and a stem 75 extends from the plunger head 73 through the spring 72 and fits in the bearing bore 71 and has a bearing ball 76 at its outer end.

The can 5 has a rim 77 and a cap 78 is placed upon the rim 77. The foot lever 33 is operated to press the head 21 downwardly into the cap 78 and press the cap downwardly through the rim 77. Then the foot lever 51 is operated to press the cam 39 downwardly against the balls 74 and press the balls 76 outwardly inside of the rim 79 of the cap 78 below the rim 77 and the friction wheel 41 engages the friction wheel 18 and rotates the cam shaft 38 thereby rotating the head 21 and causing the balls 76 to run around inside of the rim 79 of the cap 78 and press the metal outwardly below the rim 77 so as to firmly hold the cap 78 in place. Then the foot levers 33 and 51 are released and the parts return to their normal positions and the sealed can 5 may be removed from the platform 4.

The operator may sit upon a bench and operate the foot lever 33 with one foot and the foot lever 51 with the other foot, or he 105 may stand upon his heels and operate the levers with his toes.

Various changes may be made without departing from the spirit of my invention as claimed.

I claim:

1. A friction top can sealer comprising a base, a post extending upwardly from the base, a platform extending forwardly from the post above the base, a shaft housing pivotally connected to the upper end of the post in a horizontal position, a spring supporting the forward end of the shaft housing, a shaft in the shaft housing, a pulley upon the rear end of the shaft, a friction wheel upon the forward end of the shaft, a bearing bracket extending forwardly from the upper end of the post, a vertical bearing in the bearing bracket, a plunger slidably and rotatably mounted in the bearing, a cam shaft 115 slidably mounted in the plunger and fixed for rotation therewith, a lever pivotally connected at its rear end and having a fork bearing downwardly upon the plunger, a spring bearing upwardly on the plunger, a fric- 120 125 130

- tion disk fixed upon the upper end of the cam shaft in condition to engage the friction wheel, a second lever pivotally connected to an arm extending from the post and bearing 5 upon the hub of the friction wheel, a bearing plate above the lever, foot levers pivotally connected to the base, links connecting the foot levers to the first and second levers, a head upon the plunger and having 10 a flat lower face and a circular periphery, plungers radially mounted in the head, a cam upon the lower end of the cam shaft for operating the radial plungers, and balls at the outer ends of the radial plungers.
- 15 2. In a friction top can sealer a head, plungers radially mounted in the head, means for operating the head to press a can cap into place, means for rotating said head, and a cam movable to engage the radial 20 plungers for operating the same so as to expand the rim of the can cap.
3. In a friction top can sealer, a head, plungers radially mounted in the head, means for operating the head to press a can 25 cap into place, a cam movable to engage the radial plungers for operating the same so as to expand the rim of the can cap, means for moving said cam, and means for rotating said head, the two last mentioned means 30 being dependently actuated.
4. In a friction top can sealer, a shaft housing pivotally mounted, a shaft in the shaft housing, a pulley upon one end of the shaft, a friction wheel upon the other 35 end of the shaft, a spring for yieldingly supporting the housing, a vertical bearing, a plunger in the vertical bearing, a head upon the lower end of the plunger, expanding means carried by the head, a 40 cam shaft mounted in the plunger and having a cam for operating the expanding means, means for lowering the plunger, means for lowering the cam shaft, and a friction disk upon the cam shaft to engage 45 the friction wheel.
5. In a friction top can sealer, a shaft housing pivotally mounted and spring supported, a friction wheel upon the shaft housing, a plunger having expanding means at 50 its lower end, a cam shaft mounted through the plunger for operating the expanding means and adapted to rotate the plunger, and a friction disk upon the cam shaft and adapted to engage the friction wheel.
- 55 6. In a friction top can sealer, a head having a flat lower face and a circular periphery, expanding plungers radially mounted in the head and extending from the periphery and having expanding means at 60 their outer ends, a moving plunger for operating the head up and down, a cam shaft slidingly mounted in the moving plunger and fixed for rotation with the same, means for reciprocating the moving plunger, means for reciprocating the cam shaft, and means 65 for rotating the cam shaft to rotate the expanding means.
7. In a friction top can sealer, a head, plungers radially mounted in the head, a cam shaft axially movable through said 70 head and fixed for rotation with the same, and means for axially moving said cam shaft and rotating the same and said head, the movement of said cam shaft operating said radial plungers.
- 75 8. In a friction top can sealer, a head, lever mechanism for axially moving said head, plungers radially mounted in the head, means for rotating said head, and a cam shaft extending through said head and axially movable to engage said radial plungers for operating the same.
9. In a friction top can sealer, a head, means for axially moving said head, plungers radially mounted in the head, a cam 85 shaft axially movable through said head and fixed for rotation with the same, and means for axially moving said cam shaft and rotating the same and said head, the movement of said cam shaft operating said 90 radial plungers.
10. In a friction top can sealer, plungers, expanding means carried by said plungers, a cam extending between said plungers and arranged for axial movement to operate said 95 expanding means, said cam being rotatably fixed relative to said plungers, rotating driving means, and a driving connection operable between said driving means and said cam when said cam is axially moved to operative position.
11. In a friction top can sealer, plungers, expanding means carried by said plungers, a cam extending between said plungers and arranged for axial movement to operate said 105 expanding means, said cam being rotatably fixed relative to said plungers, a bearing arranged for swinging movement axially of said cam and plungers, a drive shaft in said bearing, and a driving connection operable 110 between said shaft and said cam when said cam is axially moved to operative position.
12. In a friction top can sealer, a support, a head arranged for axial movement, expanding means carried by said head, a cam 115 shaft extending through said head and arranged for axial movement to operate said expanding means, levers for said head and cam shaft carried by the support, and independent operating mechanism for each of 120 said levers for respectively actuating said head and cam shaft.

In testimony whereof I have signed my name to this specification.

FRANK CRAWFORD.
